UNIVERSAL HEDDLE BACKER FOR WARP
DRAWING MACHINES

Charles B. Crandall and Franklin L. Townsend,
Loves Park, Ill., assignors to Barber-Colman
Company, Rockford, Ill., a corporation of Illi-
nois

Application October 26, 1951, Serial No. 253,428

18 Claims. (Cl. 28—46)

1

This invention pertains to means for compacting steel heddles during the drawing-in operation of a warp drawing machine, and the general object is to provide a heddle backer which is universally usable with heddle frames of differing widths. The present trend toward weaving cloth with more complicated patterns has led to the use of longer heddles and therefore of wider heddle frames in order to provide for enough movement of the harnesses to form the shed, the width of the heddle frames varying according to the number of harnesses in use.

It is a further object of the invention to provide a heddle backer which may easily be installed in the heddle frame and which may be relied upon to remain in place without falling out.

Another object is to provide a backer which will avoid any tendency to bind in the heddle frame.

Another aim of the invention is to provide a heddle backer of low manufacturing cost.

These and other objects and advantages of the invention will appear from the following description of an illustrative embodiment constructed in accordance with the invention, the description being taken with the accompanying drawing, in which:

Figure 1 is a fragmentary side elevational view showing a heddle frame in a warp drawing machine carrying a mass or pack of steel heddles and illustrating the improved heddle backer.

Fig. 2 is a perspective view of the compacting device or backer.

Fig. 3 is a vertical sectional view of the heddle backer taken along the line 3—3 in Fig. 1; and

Fig. 4 is an enlarged fragmentary side elevational view similar to Fig. 1.

Referring first to Fig. 1, 5 designates one of the usual group of heddle frames suitably supported in the framework 6 of a warp drawing machine. A traveling carriage 7 is slidable on the main frame and the heddles are released in the usual manner under the control of a spiral release key 8 carried by a shaft 9 which extends through suitable key slots in the heddles.

The heddle frame comprises upper and lower parallel bars 11 and 12 suitably connected at their opposite ends as by means of U-shaped metallic members 13. Carried by the end members of the frame are a pair of stringer bars or rails 14 upon which a pack of heddles 15 are slidably supported for traveling movement with the carriage 7.

In accordance with this invention, the heddle

2

backer 16 is so constructed that it may be carried on one only of the heddle supporting rails 14, preferably the lower rail, so as to be effective notwithstanding variations in the spacing of such bars. To this end the backer is made in two relatively slideable members or parts respectively provided with gripper means for engagement with opposite edges of the supporting rail and firmly held in operative position subject to disengagement by relative movement between the two sections.

As best shown in Figs. 2 and 3, the improved backer comprises an elongated body member 17 having its upper end shaped for engagement with the heddle pack, and a gripping member 18 slideable relative to the body. One of these parts, in this instance the body 17, is of sectional construction, having two relatively adjustable sections with a disengageable connection between them to provide for adjustment of the overall length of the heddle backer.

As shown, one section of the body 17 consists of an elongated plate 19. The other is in the form of an elongated housing 20 telescoping over the plate 19. The housing 20 consists of an inwardly flanged channel having a flat rear wall 21, a pair of side walls 22 extending forward from the rear wall 21, and a pair of front retaining flanges 23.

The gripping member 18 preferably includes an elongated plate 24 which is telescopically received in the channel-shaped housing 20 in front of the body plate 19. For this purpose the side walls 22 of the housing 20 are made of a width sufficient to accommodate both plates 19 and 24.

The body plate 19 and the gripping plate 24 are respectively provided with opposed rail engaging means comprising in this instance pairs of spaced rollers 25 and 26 rotatably mounted on the respective plates. The rollers 25 are mounted on the front side of the lower end of the body plate 19 for engagement with the lower edge of the rail 14; and the rollers 26 are mounted on the rear side of a portion 28 of the gripper plate 24, which portion is offset forwardly to bring the rollers 26 into vertical alignment with the rollers 25. The offset portion 28 extends downwardly in front of the bar 14 to retain the upper rollers 26 on the bar; and the lower rollers 25 are retained on the lower edge of the bar 14 by an angle bracket 29 on the lower end of the body plate 19.

Preferably the backer body plate 19 and the gripper plate 24 are yieldably urged in a direction to carry the two pairs of rollers 25 and 26 into gripping engagement with the upper and lower

edges respectively of the rail 14. For this purpose a coiled contractile spring 30 is stretched between posts 31 and 32 mounted on the plates 19 and 24 respectively, the post 31 extending through a longitudinal slot 34 in the plate 24. The length of the slot 34 fixes the extent of opening and closing movements of the plates 19 and 24.

The backer body 17 includes a heddle engaging member, which in this instance comprises a horizontal tubular member 35 welded to the upper end of the channel-shaped housing 20. The tubular member 35 also serves as means to guide the upper end of the heddle backer 16 along the heddle releasing shaft 9. The tubular member 35 has a longitudinal slot 36 extending the full length of its upper side to admit the heddle-releasing shaft. Thus the tubular member forms a channel in which the heddle-releasing shaft is normally positioned.

The body 17 of the heddle backer is longitudinally extensible to compensate for varying distances between the supporting bar 14 and the release shaft 9. This is accomplished by adjusting the extent to which the housing 20 and the body plate 19 are telescoped. A detent device may be provided to maintain the adjustment of the heddle backer. In this instance, the detent device includes a series of longitudinally spaced holes 38 in the body plate 19, together with a latching pin 39 carried by a leaf spring 40 mounted on the rear wall 21 of the housing 20. The pin 39 extends through an aperture 39a in the rear wall 21 into any selected one of the holes 38.

During the warp drawing operation, the pack of heddles 15 exerts a force on the tube 35 carried at the upper end of the heddle backer 16, so that the upper portion of the heddle backer 16 tends to tilt to the right as seen in Fig. 1. The force thus exerted tends to spread apart the rollers 25 and 26, and thereby to shift the gripping member 18 with respect to the body member 17. While the spring 30 tends to resist such tilting movement of the backer, additional means is preferably provided for positively locking the body and gripper member against relative spreading movement when once the backer is mounted in the heddle frame. In this instance, spreading of the members is prevented by a latch 41 which is movably mounted on one of the members 17 or 18 and engageable with stop means on the other member. The spring anchor post 31 on the body plate 19 may be utilized as the stop means, and the latch 41 may be mounted by 55 means of a pivot 42 on the gripping plate 18. As shown, the latch has a depending arm 44 carrying a laterally extending finger 45 at its lower end. The finger 45 provides one or more upwardly facing shoulders which are engageable with the lower side of the spring anchor post 31. Two shoulders 46 and 48 are provided to accommodate two different widths of heddle supporting bars 14. The latch arm 44 may have an outwardly turned edge or flange 49 to strengthen the 60 arm and to serve as a finger grip for manipulating the latch.

In some instances, it may be desirable to provide means for increasing the frictional resistance to sliding movement of the heddle backer 70 16 along the supporting bar 14. Such means may take the form of a leaf spring 50 having one end mounted on the lower end of the body plate 19 and the other end positioned to engage the lower edge of the supporting bar 14.

The heddle backer is installed in the heddle frame by first positioning the rollers 25 on the top of the supporting bar 14. The latch 41 is then released by rotating the latch arm 44 until the latch finger 45 is clear of the spring anchor post 31. The body member 17 and the gripping member 18 are spread apart against the force of the spring 30 by pushing down on the tubular guide 35 so that the bracket 29 can be hooked over the lower edge of the supporting bar 14. The downward spreading force is then removed to allow the spring to move the jaw rollers 25 and 26 into gripping engagement with the bar 14. The tubular guide 35 is positioned around the 15 heddle releasing shaft 9 by passing the slot 36 over the shaft. Next, the latch 41 is released, and it moves by gravity into a position in which one of the shoulders 46 or 48 is closely adjacent the lower side of the spring anchor post 31. The 20 clearance between the posts 31 and the latch 41 may be as small as manufacturing tolerances permit. The heddle backer 16 is then slid along the bar 14 to move the guide tube 35 against the pack of heddles 15. By preventing downward 25 movement of the spring anchor post 31 with respect to the gripping plate 24, the latch 41 prevents the force exerted by the heddles from tilting the heddle backer.

It will be apparent that the heddle backer of this invention is constructed for secure attachment to the heddle frame so that the backer cannot become detached from the frame accidentally. The various component parts of the backer may be fabricated and assembled with unusual 35 facility and economy.

We claim as our invention:

1. In a heddle backer for compacting heddles in a heddle frame having a heddle supporting rail, the combination of a member having means engageable with one edge of said rail, a second member having means engageable with the other edge of said rail, and means for holding the respective members in gripping relation to the rail, one of said members having a heddle engaging portion.

2. In a heddle backer for compacting heddles in a heddle frame having a heddle supporting rail, the combination of a member having means engageable with one edge of said rail, a second member having means engageable with the other edge of said rail, and spring means for holding the respective members in gripping relation to the rail, one of said members having a heddle engaging portion.

3. In a heddle backer for compacting heddles in a heddle frame having a heddle supporting rail, the combination of a member having means engageable with one edge of said rail, a second member having means engageable with the other edge of said rail, and means for positively holding the respective members in gripping relation to the rail, one of said members having a heddle engaging portion.

4. In a heddle backer to compact heddles in a heddle frame having a heddle supporting rail, the combination comprising a body member, a pair of relatively movable rail engaging and guiding means on the member for slidably and detachably securing the body member to the rail, said means including respective pairs of spaced rollers to engage the rail, and means on the body member to engage the heddles.

5. In a heddle backer to compact heddles in a heddle frame having a heddle supporting rail, the combination comprising a pair of relatively

movable rail engaging means for slidably and detachably securing the backer to the rail, said means including respective pairs of spaced rollers to engage the rail, and spring means operative to engage the rail to provide frictional resistance to sliding movement of the backer relative to the rail.

6. In a heddle backer to compact heddles in a heddle frame having a heddle supporting rail, the combination comprising a body member having a pair of parts connected for relative longitudinal adjusting movement to adjust the length of the member, means on one end of the body member for slidably securing the member to the rail, and means on the body member to engage the heddles.

7. In a heddle backer to compact heddles in a heddle frame having a heddle supporting rail, the combination comprising a body member having two parts connected for relative longitudinal adjusting movement to adjust the length of the member, detent means to maintain the relative adjustment of the parts, means on one end of the body member for slidably securing the member to the rail, and means on the body member to engage the heddles.

8. For a warp drawing machine having a heddle release shaft, a heddle backer to compact the heddles in a heddle frame having a heddle supporting rail, the combination comprising a member to extend between said rail and shaft, means at one end of the member for slidably attaching the member to the rail, and guiding means at the other end of the member to engage with the release shaft.

9. For a warp drawing machine having a heddle release shaft, a heddle backer to compact the heddles in a heddle frame having a heddle supporting rail, the combination comprising a member to extend between said rail and shaft, means at one end of the member for slidably attaching the member to the rail, and guiding means at the other end of the member to engage with the release shaft, said member being longitudinally extensible to compensate for varying distances between the heddle supporting rail and the release shaft.

10. A heddle backer for compacting heddles in a heddle frame having a heddle supporting rail, said backer comprising, in combination, a body having means engageable with one edge of said rail, a member slidable relative to the body and having means engageable with the other edge of the rail, spring means urging the respective rail engaging means in a direction to grip the rail, and means for positively locking said body and said member against relative movement.

11. A heddle backer for compacting heddles slidably on a pair of supporting rails in a heddle frame with a heddle release shaft passing through the heddles, said backer comprising an elongated body having a guide at one end for engagement with the heddle release shaft, means on the other end of the body engageable with one edge of one of said heddle supporting rails, a member slidably mounted with respect to the body and having means engageable with the other edge of said one rail, and means acting upon said body and said member respectively to hold the respective gripping means in gripping relation to the rail, said body being longitudinally extensible.

12. A heddle backer for compacting heddles slidably on a pair of supporting rails in a heddle frame with a heddle release key passing through

the heddles, said backer comprising an elongated body having a guide at one end for engagement with the heddle release key, means on the other end of the body engageable with one edge of one of said heddle supporting rails, a member slidably mounted with respect to the body and having means engageable with the other edge of said one rail, and means acting upon said body and said member respectively to hold the respective gripping means in gripping relation to the rail, said body being longitudinally extensible, and said holding means including a latch device positively locking the member against sliding movement relative to the body.

13. A heddle backer for mounting upon one of the heddle supporting rails of a heddle frame in a warp drawing machine, comprising a body having means engageable with one edge of said rail, a member slidable relative to the body and having means engageable with the other edge of the rail, and a latch device for positively locking said member against sliding movement relative to the body whereby to maintain the heddle backer against tilting movement relative to the rail.

14. A heddle backer for mounting upon one of the heddle supporting rails of a heddle frame in a warp drawing machine, comprising a body having means engageable with one edge of said rail, a member slidable relative to the body and having means engageable with the other edge of the rail, spring means connecting the body and member to urge the respective rail engaging means into gripping relation to the rail, and a latch device for positively locking said member against movement relative to the body, said latch device being disengageable to permit such relative sliding movement against the action of said spring means.

15. A heddle backer for mounting on a heddle supporting rail comprising, in combination, a body member having means engageable with one edge of the rail to permit movement of the member longitudinally of the rail but held against lateral movement relative thereto, a second member mounted for sliding movement relative to the first member and having means engageable with the opposite edge of the rail while permitting movement longitudinally thereof, one of said members having a guide for engagement with a heddle release key extending through the heddles and serving to limit lateral movement of the backer and means for holding said members in gripping relation to the rail to resist tilting movement of the backer relative to the rail.

16. A heddle backer for mounting on a heddle supporting rail comprising, in combination, a body member having means engageable with one edge of the rail to permit movement of the member longitudinally of the rail, a second member mounted for sliding movement relative to the first member and having means engageable with the opposite edge of the rail, said rail engaging means being operative to hold the backer against lateral movement while permitting movement longitudinally, one of said members having a guide for engagement with a heddle release key extending through the heddles and serving to limit lateral movement of the backer, and means for holding said members in gripping relation to the rail.

17. A heddle backer for warp drawing machines having a heddle frame with a heddle supporting rail and a heddle release shaft, said backer comprising a member to extend between the rail and the release shaft, means on one end of the mem-

ber for slidably and detachably securing the member to the rail, and an outwardly open guide at the other end of the member having side members to engage with the opposite sides of the release shaft.

18. A heddle backer for warp drawing machines having a heddle frame with a pair of heddle supporting rails and a heddle release shaft, said backer comprising a pair of adjacent elongated plates, an extension member telescoping over the plates for adjusting the length of the backer, the plates being relatively slidable in the extension member, a pair of rail engaging means on the respective plates to grip the opposite edges of the rail, a spring urging the plates in a direction to close the rail engaging means, a latch to restrain

opening movement of the plates to prevent tilting of the backer on the rail, and means on the extension member forming a channel to receive the release shaft for maintaining the shaft and the backer in lateral alinement.
